UNITED STATES PATENT OFFICE.

JOSEPH PIEPER, OF WEST POINT, IOWA.

PACKING EXPANDER FOR PISTONS, ETC.

Application filed October 10, 1925. Serial No. 61,801.

This invention relates generally to improvements in pistons or buckets, and has particular reference to means for expanding the packing mounted thereon.

5 An important object of the invention is to provide means on a piston for expanding the packing member carried thereby so as to cause the packing to be pressed firmly against the cylinder walls.

10 A further object of the invention is the provision of means for expanding the piston packing, designed so as to be fitted upon the conventional type of pistons and buckets now in use.

15 A still further object of the invention is the provision of a packing expander of a simple yet durable nature and formed so as to permit comparatively long usage.

Other objects and advantages of this invention will become apparent as the description progresses.

In the accompanying drawing forming a part of this specification and in which like numerals are employed to designate corresponding parts throughout the same:

Figure 1 is a vertical sectional view through a cylinder showing a valved piston embodying my invention in an elevational view partially broken away to show the interior construction, and

Figure 2 is a transverse sectional view taken on the line 2—2 of Figure 1.

In the drawing, wherein for the purpose of illustration is shown the preferred embodiment of my invention, the numeral 5 generally designates a conventional type of cylinder such as is customarily employed in water and oil wells. As is well known, these cylinders are usually in the form of comparatively long pipe sections connected together and extending to comparatively great depths into the ground. The water or oil is elevated from the bottom of the tubing, in the present instance, through the instrumentality of a valved piston or bucket generally indicated at 6.

The piston is composed of two sections, an upper body section 7 composed of a circular ring 8 internally screw threaded and 50 a bonnet 9. This bonnet is formed with a central circular disk provided at its center with an internally screw threaded opening for connection of the piston rod 10, this central disk being connected with the annular ring 8 by a plurality, in the present instance, four angular ribs 11.

Threadedly engageable with this body section is a lower section 12 embodying a tubular sleeve 13 provided on its lower edge with an outwardly directed horizontal flange 14. The sleeve 13 is externally screw threaded so as to engage the threads formed on the interior of the ring 8 for connection of these sections. As is readily apparent, from Figure 1, a packing ring 15 is mounted 60 between the flange 14 of the bottom section and the ring 8 of the upper section, this packing ring being of angular formation so as to provide a horizontal portion engageable by the piston sections and a vertical 65 cylindrical portion adapted to snugly contact with the interior walls of the cylinder or tubing.

In the present type of piston or bucket, the passage of matter through the piston is controlled by a vertically operable valve 16 embodying a circular top plate or disk 17 adapted to be properly fitted upon the upper edge of the sleeve 13, the central portion of the said circular plate or disk carrying a 70 downwardly depending stem 18 so as to prevent displacement of the valve.

As will be understood by those familiar with this art, the packing member 15 constructed of leather or similar pliable material becomes worn in a comparatively short time and continuous use of the piston weakens the contact of the packing ring with the side walls of the tubing so that the efficiency of the piston is impaired. My invention relates particularly to means for overcoming the tendency of the packing ring to work away from the walls of the tubing and thus prevent leakage of the matter between the packing and the walls.

I accomplish this by the provision of a spring steel band 20 coiled about the piston body ring 8 between this ring and the outer packing ring, this spring being preferably formed in a double coil and arranged so as to normally expand, thus forcing the horizontal ring of the packing tightly against the cylindrical walls. In order to prevent longitudinal displacement of the spring 20 and at the same time permit lateral expansion, I provide a plurality of transversely extending pins 21, one such pin being inserted in each of the piston body ribs 11 and projecting substantially outward. The outward projections of these pins will prevent upward movement of the spring 20 and thus retain this member in

position. It is thus apparent, that although the outer horizontal ring of the packing member will become worn by continuous movement of the piston through the tubing, the packing ring will retain its tight fitting qualities by the provision of the resilient spring member 20, as this spring will at all times exert a pressure upon the packing ring and tend to expand this member. This structure will materially prolong the life of the packing ring and in this manner create a substantial saving, and in addition thereto will cause the piston or bucket to operate efficiently until the packing has entirely worn out.

It is to be understood that the form of my invention herewith shown and described is susceptible of modification, and that various changes as to the shape, size and arrangement of parts may be resorted to without departing from the spirit of the invention or the scope of the subjoined claims.

Having thus described my invention, I claim:

1. In combination with a pump piston including a cylindrical body member provided with upwardly directed extensions, an interior sleeve threadedly connected with the annular body member having an outwardly directed annular flange on its lower edge, and a packing ring of angular cross section clamped between the lower edge of the annular body member and the sleeve flange; packing expanding means including a resilient normally expanded band disposed between the cylinder engaging portion of the packing ring and the exterior surface of the annular body member so as to maintain the packing pressed firmly against the cylinder walls, and a plurality of pins associated with the upper extending portions of the annular body member having the outer ends projecting laterally to engage the upper edge of the resilient band to retain the same in proper position.

2. In combination with a pump piston including a circular body member having

upwardly directed extensions on its upper edge provided with transverse bores therethrough, an interior sleeve threadedly connected with the circular body member having an outwardly directed flange formed on its lower edge and disposed below the circular body member, and a packing ring of angular cross section having its horizontal portion firmly clamped between the lower edge of the circular body member and the sleeve flange and its outer portion in contacting position against the cylinder walls; packing expanding means including a resilient expandible band disposed between the cylinder contacting portion of the packing ring and the outer periphery of the circular body member tending to normally press the packing firmly against the cylinder walls, and a plurality of pins removably mounted in the transverse bores formed in the circular body projections having their outer extremities projecting outwardly to engage the upper edge of the band to prevent displacement thereof.

3. Means for expanding the packing of a piston into engagement with the wall of a cylinder, wherein the piston includes a cylindrical body member and an annular sleeve threadedly connected with the interior of the body member having an outwardly directed annular flange formed at its lower edge so as to clamp the inwardly directed flange of the packing between the lower edge of the body member and the inner upper face of the sleeve flange, comprising a normally expanded resilient band adapted to be disposed between the cylinder wall engaging portion of the packing and the outer periphery of the cylindrical body member so as to automatically maintain the packing ring in proper engagement with the cylinder wall, and pins adapted to be rigidly associated with the upper end of the body member so as to project outwardly across the upper edge of the band and retain the latter in place.

In testimony whereof I affix my signature.
JOSEPH PIEPER.
